INVENTOR :-

Edwin John Flewitt.
Per: Arthur Gadd

ATTORNEY:-

UNITED STATES PATENT OFFICE.

EDWIN JOHN FLEWITT, OF RAWTENSTALL, ENGLAND, ASSIGNOR TO HOYLE HOYLE & CO. LIMITED, OF RAWTENSTALL, ENGLAND.

ELASTIC CLOSURE FOR LADIES' BOOTS.

Application filed March 12, 1926, Serial No. 94,282, and in Great Britain December 29, 1925.

The invention relates to Russian boots for ladies' wear, and has for object to provide the same in such manner as to enable them to be shaped in a desirable manner, 5 or conform to the curvature of the limb of the user, without being rendered thereby difficult to pull on or off.

As is well known, this last-named difficulty largely accounts for the boots at the 10 upper portions thereof being made in more or less straight form, or without desirable shape.

According to my invention, I make the boot or shape the same at the upper portion 15 in suitably curved manner, but so that said upper portion, either wholly or in part, is capable of being stretched to greater width for pulling-on and pulling-off purposes.

This I accomplish by providing what may 20 be termed knife-edge slits, up each side by preference, through the material of the upper part of the boot, in suitable form and extent, and within the upper part named, behind the slits aforesaid, I stitch or attach 25 an area or areas of india-rubber or elastic material. The stitches for the same, when employed, I prefer to provide parallel to the slits and between the same, as well as beyond the same at each side of the area 30 covered by said slits. The elastic material is preferably of the same or similar colour to the colour or shade of the boot or upper portion thereof.

With reference to the accompanying 35 drawings, Fig. 1 is a plan view of Fig. 2, the latter being an elevation of a Russian boot provided according to my invention. In said latter figure, the stitches for the elastic material behind are not indicated, and in 40 Fig. 1 the material forming the upper part of the boot is exaggerated in thickness for the sake of clearness.

Fig. 3 is an enlarged view of a piece of 45 the upper portion of the boot, before stretching has been accomplished, and Fig. 4 is a similar view during stretching referred to. The stitches are not shown in said Fig. 4. Fig. 5 is a modification of Fig. 1.

a is the upper portion of the boot illustrated, and according to my invention, knife-edge slits *b* are provided in or through the same, the area covered thereby being according to desire or necessity. *c* represents an area or sheet of india rubber or elastic material attached behind the slit portion 55 named, which elastic material is assumed to be stitched through the upper portion as indicated at *d* on each side of each slit *b*.

But it is obvious that the elastic material could be, for instance, cemented along 60 the lines occupied by the stitches shown. Said stitches are indicated as being very open in form merely to prevent confusion.

The effect attained is that, not only can the upper portion of the boot be stretched 65 sufficiently for being pulled on or off the limb of the user, but also that, in wear the slits are so far invisible as, in conjunction with the stitches and indentations produced thereby, to result in a merely ornamental 70 effect.

It is obvious that the arrangement of lines of stitches, and lines of slits are not confined to those shown, the area of the latter being 75 capable of variation. For example, in Fig. 5, the area covered by parallel slits is different to that covered by the curved ones indicated, laterally speaking.

I claim:

Russian boots for ladies' wear with shaped 80 upper portions for conforming nearly to the curvature of the limbs of the users, slits in the material of said upper portions, elastic material or backing behind the area covered by said slits, said backing attached to the 85 upper portions within the boots by stitches of thread down each side of each slit aforesaid, whereby the latter are practically rendered invisible during normal wear, and an ornamental effect with the stitches and resulting indentations produced, substantially 90 as herein set forth.

In testimony whereof I have affixed my signature.

EDWIN JOHN FLEWITT.
